UNITED STATES PATENT OFFICE.

MELVIN SOLOMON GROH, OF TORONTO, ONTARIO, CANADA, ASSIGNOR TO JOSEPH MERCADANTE, OF NEW YORK, N. Y.

ELECTRIC HOUSEHOLD REFRIGERATOR.

Application filed December 31, 1924. Serial No. 759,003.

To all whom it may concern:

Be it known that I, MELVIN SOLOMON GROH, a citizen of Canada, residing at Toronto, in the county of York, in the Province of Ontario, Canada, have invented a new and useful Improvement in Electric Household Refrigerators, of which the following is a specification.

My invention relates to an electric household refrigerator adapted to be more efficient and quieter in operation than those heretofore in use.

I attain this object by the mechanism illustrated in the accompanying drawings, in which:

Fig. 1 is a vertical sectional side view of my device taken on the line 1—1 of Fig. 2; Fig. 2 is a vertical sectional front view of my device taken on the line 2—2 of Fig. 1. 20 Similar letters refer to similar parts throughout the several views.

A is an outside housing of wood, metal or any other appropriate material. B is a board of cork or other non-conducting material. C is an upper door opening into the cooling chamber A¹¹. D is a lower door opening into storage chamber A¹². E are lattices permitting the passage of air through condensing chamber A¹⁰. L are wire meshes permitting the passage of air through condensing chamber A¹⁰. F is the closed bottom housing of condensing chamber A¹⁰ with machine spring supports N, adapted to absorb vibration, and supporting the water tight base M, with surrounding water-tight rail M³, which sustains rotary pump Q enclosed in housing R with fins S, and also supporting condensing coil T and electric motor O. Supports N are preferably three in number, so that by loosening two of them, and leaving fixed the one directly under tube V², the entire base M and its contents can be swung out of the refrigerator for adjustment when necessary. W is a pipe leading from the outlet of pump Q to the intake end of condensing coil T. P is an air fan mounted on driving shaft Q¹, which connects electric motor O with pump Q. V is the discharge pipe from the lower end of condensing coil T, and U is the intake pipe leading into the intake end of pump Q. M² is a manifold through which pipes U and V pass. G is an outside flooring, with boards H of cork or other non-conducting material lying between, and sep-

arating chamber A¹⁰ from chamber A¹². V² is a protecting tube containing pipes U and V, and V³ is a drip drain pipe adapted to carry any drip water or moisture from floor J down onto coil T and thence down onto water-tight base M, thus putting a cooling fluid outside the lower portion of condensing coil T, and thus aiding the condensing function of said condensing coil T. Air fan P, by circulating the air, gradually evaporates the water in base M, thus further cooling coil T. J² is a drip plate adapted to prevent any drip moisture from falling through cold air flue J⁴ from above, and J³ is a guard to prevent any drip moisture from running along floor J into cold air flue J⁴. K is a vertical wall leaving open spaces at the top and bottom, so as to permit a circulation of warm air from the top of storage chamber A¹² into the top of cooling chamber A¹¹, and to permit a circulation of cool air from the bottom of cooling chamber A¹¹ through cold air flue J⁴ into the bottom of storage chamber A¹². It will be understood that storage chamber A¹² may be fitted with shelves, and with one or more doors as is usual. W² is a diagrammatic view of a thermostat connected (by wires not shown) with motor O, and adapted to start motor O when the temperature of the air in storage chamber A¹² rises above a certain point, and to stop motor O when the temperature of the air in storage chamber A¹² falls below a certain point. X is a control valve adapted to control the flow of liquid refrigerant from pipe V into liquid refrigerant Z. Z¹ are depending loop tubes, adapted to carry liquid refrigerant from container Z and to freeze water into ice in containers Z³ in housing Z⁵. Z¹¹ are depending loop tubes, adapted to carry liquid refrigerant from container Z. Z² are fins homogeneously connected to said tubes Z¹ and Z¹¹. The said brine or water or other freezing liquid contained in said fins Z² will absorb the heat from the outside air as hereinafter explained, and will transmit said heat through tubes Z¹ and Z¹¹ into the liquid refrigerant therein contained. It will be observed that fins Z² almost completely fill the space of cooling chamber A¹¹, and that the top line of said fins Z² are substantially in horizontal alignment with the top of vertical wall K, the result being that the air circulation through cooling chamber A¹¹ is largely increased, as the structure disclosed

admits no air whatever to cooling chamber A¹¹ except from the extreme top of storage chamber A¹², which necessarily means the air of the highest temperature therein. 6 When said warmer air is thus drawn into the top of cooling chamber A¹¹, the heat absorption by fins Z² and tubes Z¹ and Z¹¹, very rapidly reduces the temperature of the air, and causes it to drop to the lower portion 10 of cooling chamber A¹¹ and thence through air flue J⁴ into the lower portion of storage chamber A¹². Thereupon the cold air will begin to absorb heat from, and thus lower the temperature of the various foods and 15 other things in storage chamber A¹², whereupon said air, with this additional heat, will rise to the top of storage chamber A¹², and the cycle of air will then begin anew.

The various elements of my complete device herein shown, including the refrigerating cooling means shown in chamber A¹¹, the air cooling device shown in chamber A¹⁰, the machine spring support N shown in the bottom F of chamber A¹⁰, the automatic control valve X shown in chamber A¹¹, the manifold M² shown in chamber A¹⁰ are each a separate and individual and divisional invention in my complete device as shown, and each of the said elements is covered by 20 a separate application for patent thereon.

I claim:

1. In an electric household refrigerator, a condensing coil located in a separate condensing chamber in the bottom of said refrigerator, a compressor adapted to convey a refrigerating medium under pressure into said condensing coil, a refrigerating cooling means located in a separate cooling chamber inside the top of said refrigerator, and a

drip drain pipe extending through the bottom floor of said cooling chamber and down through the top floor of said condensing chamber, the lower end of said drip pipe being over the condensing coil. 40

2. In an electric household refrigerator, 45 a cooling chamber containing refrigerating cooling means including a container, tubes each end of which open into said container, and fins the sides of which are attached to said tubes, said tubes and fins transversely 50 filling practically the entire side and bottom space of said cooling chamber.

3. In an electric household refrigerator, a condenser adapted to condense a refrigerating medium therein contained, a compressor adapted to convey said refrigerating medium under pressure into said condenser, a water-tight pan open at the top and supporting said condenser, the lower coils of the condenser being below the top of said 60 pan, a cooling element in the refrigerator, means for collecting the condensed water from the cooling element, means for conveying said condensed water from the cooling element into the pan, and an air fan adapted 65 to cool said condenser by means of air circulation and to evaporate the condensed water in said pan. 55

4. In an electric household refrigerator, 70 a condensing coil, a pump and an air fan inside of said condensing coil, a member adapted to support said condensing coil, pump and air fan, and three machine spring supports sustaining said member, one of said machine spring supports being directly beneath the vertical alignment of the intake and discharge pipes of said pump. 75

MELVIN SOLOMON GROH.
